TUYÈRE

Howard F. Lawrence, Philadelphia, Pa., assignor,
by mesne assignments, to American Engineering
Company, Philadelphia, Pa., a corporation
of Pennsylvania

Application November 30, 1940, Serial No. 368,008

10 Claims.

(Cl. 110—44)

This invention relates to stoker furnaces, and more particularly to the tuyères employed in such devices.

One object of the present invention is to provide a tuyère block construction adapted for assembly with similar tuyère blocks in stepped relation, which is so constructed that draft air is evenly distributed around the entire discharge end thereof.

Another object is to provide a tuyère block having novel locking mechanisms associated therewith which effectively secures the tuyère block in position.

A further object is to provide a novel mechanism associated with a tuyère block which enables ready replacement of a damaged member without requiring the removal of an entire stack of tuyère blocks.

A further object is to provide a generally improved and efficient tuyère block which assures proper distribution of air to the fuel bed under all conditions of operation.

Other and further objects will become apparent as the description of the invention progresses.

Of the drawings:

Fig. 1 is a longitudinal sectional view taken through one of the retorts of the stoker showing an adjacent row of the tuyère blocks comprising the present invention.

Fig. 2 is an enlarged side elevational view of several tuyère blocks showing the locking devices for holding them in position.

Fig. 3 is a view of the bottom side of a tuyère block showing the construction of the air distributing means and of the locking means for holding the tuyère block in position.

Fig. 4 is a side elevational view of the tuyère block shown in Fig. 3.

Fig. 5 is a sectional view taken substantially along line 5—5 of Fig. 2.

Fig. 6 is a sectional view taken substantially along line 6—6 of Fig. 2.

Fig. 7 is a perspective view of a locking key for holding certain of the tuyère blocks in position, and

Fig. 8 is a side view of a slightly modified construction.

Referring to the drawings, and more particularly to Fig. 1 thereof, the numeral 1 indicates generally a furnace having a stoker 2 provided therein. Stoker 2 is of the multiple retort underfeed type shown, for example, in Patent No. 1,443,202, and to which reference may be had for a detailed description thereof. Stoker 2 comprises a series of alternately disposed retorts 3

and tuyère rows 4. Fuel is fed to the retorts 3 by any suitable feeding mechanism (not shown), the fuel entering through an opening 3a provided in the front wall 5 of the furnace. The furnace 1 is bounded at the sides by walls 6, only one of which is shown. The fuel fed to the retorts 3 completely fills them and overflows onto the tuyère rows 4 provided adjacent thereto. In normal operations of the furnace a fuel bed of 2 or 3 feet in thickness is maintained. Fuel is underfed along the stoker by a series of pushers 7 provided at the bottom of each retort 3, the fuel being fed to dump plates or to an ash pocket (not shown) at the rear of the stoker in a well known fashion, from which it may be removed from time to time by any suitable mechanism.

As shown more particularly in Figs. 1 and 2, each tuyère row 4, comprises a series of substantially flat plate-like tuyère blocks 8 arranged in superimposed stepped relation. Each tuyère block comprises a relatively flat body portion 9 having a substantially rectangular air inlet end 10 and a substantially rounded discharge end 11. Depending from each side of body portion 9 are 25 a pair of supporting members 12, 12. Each supporting member 12 is flat at the bottom thereof, as shown at 13 (Figs. 3 and 4) and terminates at the forwardly disposed end in an inclined supporting portion 14, which in assembly rests upon 30 the upper surface of a side plate 15 of the retorts 3. The side plates 15, 15, as will be observed upon reference to Figs. 1 and 2, incline downwardly from front to rear of the stoker.

When the terms "front" and "rear" are employed herein it is to be understood that the term "front" indicates that portion of the member extending toward the right (Fig. 1) or front wall 5 of the furnace, and when the term "rear" is employed that portion of the member extending toward the left or rear of the furnace is indicated.

As shown more particularly in Fig. 3, a rib 16 is provided substantially on the longitudinal center line of each tuyère block 8 near the discharge end 11 thereof. A hook 17 integral with and depending from the forward end of rib 16 is adapted in assembly to extend through the slot 18 of the next lower tuyère block of the series, and engages the rearwardly disposed wall 18' 45 thereof, as shown in Figs. 1 and 2. The slot 18 is open at the forward end thereof and is disposed in longitudinal alignment with hook 17, as shown more particularly in Fig. 3. Extending forwardly from hook 17 are a pair of ribs 19. 50 These ribs diverge slightly from hook 17, as

shown at 20, and then extend in parallel relation, as shown at 21. The forwardly disposed ends are slightly beveled, as shown at 22.

The inner surfaces of supporting members 12, 12 are substantially parallel near the air inlet end of the tuyère block, as shown at 23 and diverge toward the discharge end as shown at 24. Disposed between the supporting members 12, 12 and the central ribs 16 and 19 are a series of relatively long ribs 25. Disposed between the relatively long ribs 25 are a series of shorter ribs 26. It will be noted that the ribs 25 are substantially rounded at the inlet or right hand ends thereof and form substantially streamline abutments to the incoming draft air. These ribs diverge toward the air discharge end 11 and thus define air passages having relatively restricted inlet ends and diverging side walls. The ribs 26 are of similar construction, they also being so arranged as to diverge toward the discharge end of the tuyère block and form with the ribs 25 a series of smaller passages having restricted inlet ends and diverging side walls. By this construction the air flowing through the various passages expands as it approaches the discharge end with the result that the velocity of the air discharging from the tuyère is relatively low. The left or discharge ends of the ribs are beveled, as shown at 27. The purpose of beveling these ribs is to keep the passages defined thereby open in the event that slag should drip over the discharge end of the tuyère block. A constant flow of air through all of the passages is thus assured and as a result the tuyère blocks will remain relatively cool during all conditions of operation.

As shown more particularly in Figs. 2, 5 and 6, the top edges of the stoker side plates 15, 15 are each provided with an inwardly extending flange 30, thereby forming extended bearing surfaces for the inclined supporting portions 14 of the tuyère blocks 8. Secured to the inner faces of flanges 30, 30 are a series of spaced longitudinally extending lugs 31, 31 which are adapted to be engaged by hooks 32, 32, secured to and depending from the body portion 9 adjacent the forwardly disposed ends of supporting members 12, 12 of the tuyère blocks 8. Supporting members 12, 12 of each tuyère block 8 have provided therein longitudinally extending recesses 33, 33 which, as hereinafter more fully described, receive locking keys 34, 34. Recesses 33, 33 are slightly longer than the keys 34, 34 and the ends thereof form pockets 33', 33' at the sides of hooks 32, 32 (Figs. 3, 5 and 6). Hooks 32, 32, together with the hooks 17 previously described, rigidly secure the tuyère block in proper position.

In order to permit ready removal and replacement of the tuyère blocks in the event that damage occurs thereto, I have provided key members 34 at certain intervals in place of the lugs 31. As shown in Fig. 1, these keys lock every sixth tuyère of each row in position. Each key 34 is substantially the same length as a lug 31 and has an offset portion 35 at one end which, as shown in Fig. 2, is adapted to engage over the forwardly disposed end of a tuyère block. Key 34 also has an offset portion 36 at the opposite end, which is adapted to be engaged by the hook 32 of the next higher tuyère block of the series and extends into a pocket 33'. The surface 37 at one end of the key engages the forward edge of a tuyère block while the hook 32 of the next higher tuyère block of the series engages the opposite end 38. In this way proper spacing of the tuyère blocks is maintained and at the same

time the tuyère blocks are effectively held in position.

To remove a damaged tuyère block the tuyère block held by keys 34 above and nearest to the damaged one is first removed. This is done by first urging the tuyère block forwardly slightly until its hook 17 clears the rearwardly disposed wall 18' of its recess 18 and the offset portion 35 clears the end of the next lower tuyère block. The keys 34 will then gravitate out of recesses 33. The keys 34 will move forwardly by this action since the walls 33' of the recesses 33 will engage the end of offset portion 35 thereof. The tuyère block is then urged upwardly until the hook 17 clears the upper surface of the next lower tuyère block when it is simply moved rearwardly out of position. There is sufficient clearance between the tuyère blocks to permit the slight upward movement necessary for the hook 17 to clear its recess 18. The tuyère blocks below the one just removed may then be removed one by one by simply sliding them forwardly to disengage the hooks 17 and 32, and then lifting them out of position. This is repeated until the damaged tuyère block is reached. A new tuyère block may then be substituted for the damaged one and the others may then be inserted in place in the usual manner, the tuyère block to be held in position by the keys 34 being the last inserted in position. Before this last mentioned tuyère block is inserted in position keys 34 are placed in the recesses 33, the ends 36, 36 thereof extending into the pockets 33', 33' and into engagement with the hooks 32, 32. The tuyère block is then moved forwardly between the tuyère blocks disposed above and below it, until the inclined supporting portions 14 engage the supporting plates 12, 12. When the tuyère block has reached this position the end surfaces 37 of the keys 34 will have cleared the end of the next lower tuyère block, the said keys will then move downwardly, the offset portion 35 falling into engagement with the upper surface of the next lower tuyère block. By this time hook 17 will have cleared the rearward wall 18' of recess 18 of the next lower tuyère block of the series. Now by movement of the tuyère block slightly rearwardly the parts will assume the position shown in Figs. 1 and 2 and upward, as well as further movement to the rear will be prevented. The movement of the fuel toward the rear during operation of the furnace has a tendency to maintain the tuyère blocks 8 in the position shown in Figs. 1 and 2.

The tuyère blocks themselves are provided with three locking hooks for securely holding them in position. However, in the event that one or more of the tuyère blocks should become damaged it is unnecessary to remove an entire row of tuyères to get at the damaged tuyère blocks, since by securing certain tuyères in position by removable keys, only a very few of the blocks need be removed in order to make the necessary replacements. Applicant has shown every sixth tuyère block to be held in position by removable keys 34. It is understood, however, that a fewer or a greater number of the tuyère members in each row may be held in position by keys, if it is so desired, without departing from the invention.

In some installations the hooks 17 may be entirely dispensed with. A construction of this character is shown in Fig. 8 wherein it will be noted that the tuyère block 8' shown therein is provided only with a pair of hooks 32', similar to the hooks 32 of the tuyères shown in Figs. 1 to 6, the hooks 17 being dispensed with. In in-

stallations of this kind the removal of the tuyère members held in position by keys is facilitated since it is apparent that when the tuyère has been so moved as to cause the keys 34 to drop out of position the tuyère member may be moved rearwardly out of position without first raising it, as was done in the previous case. This may be accomplished since it will be seen that the hooks 32 do not extend below the lower extremity of the tuyère block.

From the foregoing description it is seen that highly desirable tuyère block constructions have been provided. By employing the locking lugs 31 on the tuyère supporting plates 15, 15 each tuyère block is maintained in its proper position with respect to these supports. By this construction the tuyère blocks do not creep toward the lower end of the stoker but remain in proper position at all times. It is also seen that damaged tuyère blocks may be readily removed and replaced by new ones.

While the embodiments herein shown and described are admirably adapted to fulfill the objects primarily stated, it is to be understood that the invention may be embodied in other forms, all coming within the scope of the claims which follow.

What is claimed is:

1. In a device of the class described, the combination of a series of tuyère blocks arranged in superimposed stepped relation, supporting means for said tuyère blocks comprising a pair of spaced vertically disposed plates, hook means depending from each of said tuyère blocks and adapted to lockingly engage the next lower tuyère block of a series for retaining one end thereof against vertical displacement, interlocking means on said tuyère blocks and said supporting plates for retaining the other end of said tuyère blocks against vertical, as well as lateral displacement, said last mentioned means comprising a series of spaced lugs provided on each of said plates, and hooks depending from each of said tuyère blocks adapted to engage said lugs.

2. In a device of the class described, the combination of a series of tuyère blocks disposed in superposed relation, spaced supporting members for said tuyère blocks, spaced lugs provided on said supporting members, and hooks provided on said tuyère blocks adapted to engage said lugs to hold one end of said tuyère blocks against vertical and lateral movement, said parts being so disposed that engagement of said hooks with said lugs is effected by a slight downward movement of said tuyère blocks along said supporting members, and disengagement of said hooks from said lugs is effected by a slight upward movement of said tuyère blocks along said supporting members.

3. In a device of the class described, the combination of a series of tuyère blocks disposed in superimposed relation, spaced supporting members for said tuyère blocks, spaced lugs provided on said supporting members, hooks provided on said tuyère blocks adapted to lockingly engage said lugs to hold one end of said tuyère blocks against vertical movement, said parts being so disposed that engagement of said hooks with said lugs is effected by a slight downward movement of said tuyère blocks along said supporting members, and disengagement of said hooks from said lugs is effected by a slight upward movement of said tuyère blocks along said supporting members, and additional locking means provided on

each of said tuyère blocks adapted to interlock with the next lower tuyère block of the series.

4. In a device of the class described, the combination of a series of tuyère blocks disposed in superimposed relation, spaced supporting members for said tuyère blocks, spaced lugs provided on said supporting members, hooks provided on said tuyère blocks adapted to lockingly engage said lugs to hold one end of said tuyère blocks against vertical movement, said parts being so disposed that engagement of said hooks with said lugs is effected by a slight downward movement of said tuyère blocks along said supporting members, and disengagement of said hooks from said lugs is effected by a slight upward movement of said tuyère blocks along said supporting members, and said hooks being disposed within the confines of said tuyère blocks proper, whereby when said hooks are disengaged from said lugs the said tuyère blocks may be moved longitudinally relative to adjacent tuyère blocks.

5. In a device of the class described, the combination of a series of tuyère blocks disposed in superimposed relation, spaced supporting members for said tuyère blocks, spaced lugs provided on said supporting members, hooks provided on said tuyère blocks adapted to lockingly engage said lugs to hold said tuyère blocks in position, said parts being so disposed that engagement of said hooks with said lugs is effected by a slight downward movement of said tuyère blocks along said supporting members, and disengagement of said hooks from said lugs is effected by a slight upward movement of said tuyère blocks along said supporting members, said hooks being disposed within the confines of said tuyère blocks proper, whereby when said hooks are disengaged from said lugs the said tuyère blocks may be moved relative to adjacent tuyère blocks, and removable key means extending between said hooks and the forward ends of the next lower tuyère blocks of the series enabling ready removal of the tuyère blocks held in position by said keys, and of the tuyère blocks disposed immediately therebelow.

6. In a device of the class described, the combination of a series of tuyère blocks disposed in superimposed relation, spaced supporting members for said tuyère blocks, spaced lugs provided on said supporting members, hooks provided on said tuyère blocks adapted to lockingly engage said lugs to hold said tuyère blocks in position, said parts being so disposed that engagement of said hooks with said lugs is effected by a slight downward movement of said tuyère blocks along said supporting members, and disengagement of said hooks from said lugs is effected by a slight upward movement of said tuyère blocks along said supporting members, said hooks being disposed within the confines of said tuyère blocks proper, whereby when said hooks are disengaged from said lugs the said tuyère blocks may be moved relative to adjacent tuyère blocks, removable key means extending between said hooks and the forward ends of the next lower tuyère blocks of the series enabling ready removal of the tuyère blocks held in position by said keys, and of the tuyère blocks disposed immediately therebelow, each of said keys having an offset portion at each end thereof, one of said offset portions overlapping a corresponding hook on one of said tuyères, and the other offset portion overlapping the forward end of the next lower tuyère block of the series, abutment means depending from said offset por-

tions, one of said abutment means engaging said hook and the other of said abutment means engaging the said forward end of the next lower tuyère block, thereby properly spacing said tuyère blocks, and said keys being adapted to be removed by simply moving the said tuyère blocks so as to cause said hooks to move away from the forward end of the next lower tuyère block a distance sufficient to disengage the offset portion thereof from the forward end of the said next lower tuyère block whereby the said keys will gravitate out of position and permit removal of the tuyère blocks held in position thereby.

7. In a device of the class described, the combination of a series of tuyère blocks disposed in superimposed relation, spaced supporting members for said tuyère blocks, spaced lugs provided on said supporting members, hooks provided on said tuyère blocks adapted to lockingly engage said lugs to hold said tuyère blocks in position, said parts being so disposed that engagement of said hooks with said lugs is effected by a slight downward movement of said tuyère blocks along said supporting members, and disengagement of said hooks from said lugs is effected by a slight upward movement of said tuyère blocks along said supporting members, said hooks being disposed within the confines of said tuyère blocks proper, whereby when said hooks are disengaged from said lugs the said tuyère blocks may be moved relative to adjacent tuyère blocks, removable key means extending between said hooks and the forward ends of the next lower tuyère blocks of the series enabling ready removal of the tuyère blocks held in position by said keys, and of the tuyère blocks disposed immediately therebelow, each of said keys having an offset portion at each end thereof, one of said offset portions overlapping a corresponding hook on one of said tuyère blocks, and the other offset portion overlapping the forward end of the next lower tuyère block of the series, abutment means depending from said offset portions, one of said abutment means engaging said hook and the other of said abutment means engaging the said forward end of the next lower tuyère block thereby properly spacing said tuyère blocks, said keys being adapted to be removed by simply moving the said tuyère blocks so as to cause said hooks to move away from the forward end of the next lower tuyère block a distance sufficient to disengage the offset portion thereof from the forward end of the said next lower tuyère block whereby the said keys will gravitate out of position and permit removal of the tuyère blocks held in position thereby, and each of said tuyère blocks hav-

ing enlarged recesses provided therein for receiving said keys.

8. A tuyère block for stoker furnaces adapted to comprise one of a series disposed in superimposed stepped relation, comprising a relatively flat body portion having a substantially rectangular air inlet end and an air discharge end, a supporting member provided at either side of said body portion, a series of ribs provided on said body portion between said supporting members defining a series of passages for draft air, a pair of locking hooks provided adjacent said supporting members adapted to lockingly engage lugs on supports for said tuyère block, and said hooks being disposed within the confines of said tuyère block whereby said tuyère block may be moved relatively to adjacent tuyère blocks.

9. A tuyère block for stoker furnaces adapted to comprise one of a series disposed in superimposed stepped relation, comprising a relatively flat body portion having a substantially rectangular air inlet end and an air discharge end, a supporting member provided at either side of said body portion, a series of ribs provided on said body portion between said supporting members defining a series of passages for draft air, a pair of locking hooks provided adjacent said supporting members adapted to lockingly engage lugs on supports for said tuyère block, and said hooks being disposed within the confines of said tuyère block whereby said tuyère block may be moved relatively to adjacent tuyère blocks.

30 said hooks being disposed within the confines of said tuyère block whereby said tuyère block may be moved relatively to adjacent tuyère blocks, and said tuyère block having an enlarged recess provided in each of said supporting members adapted to receive a locking key.

10. A tuyère block for stoker furnaces adapted to comprise one of a series disposed in superimposed stepped relation, comprising a relatively flat body portion having a substantially rectangular air inlet end and an air discharge end, a supporting member provided at either side of said body portion, a series of ribs provided on said body portion between said supporting members defining a series of passages for draft air, a pair of locking hooks provided adjacent said supporting members adapted to lockingly engage lugs on supports for said tuyère block, said hooks being disposed within the confines of said tuyère 40 block whereby said tuyère block may be moved relatively to adjacent tuyère blocks, said tuyère block having an enlarged recess provided in each of said supporting members adapted to receive a locking key, and additional locking means depending from said tuyère block intermediate the sides thereof.

HOWARD F. LAWRENCE.
